CLAIM

The ornamental design for a battery with cable as shown and described.

DESCRIPTION

FIG. 1 is a top front isometric view of a battery with cable showing the claimed design;

FIG. 2 is a bottom rear isometric view thereof;

(Continued)

FIG. 3 is a front elevation view thereof;
 FIG. 4 is a rear elevation view thereof;
 FIG. 5 is a left side elevation view thereof;
 FIG. 6 is a right side elevation view thereof;
 FIG. 7 is a top plan view thereof; and,
 FIG. 8 is a bottom plan view thereof.

The cable is shown with break lines in its length. The break lines and the appearance of any portion of the cable between the break lines form no part of the claimed design.

1 Claim, 6 Drawing Sheets
